UNITED STATES PATENT OFFICE.

CHARLES PHILIPPE ALTMANN, OF LYONS-VAISE, FRANCE.

WATER-TUBE BOILER.

SPECIFICATION forming part of Letters Patent No. 715,737, dated December 16, 1902.

Application filed December 10, 1901. Serial No. 85,377. (No model.)

To all whom it may concern:

Be it known that I, CHARLES PHILIPPE ALTMANN, a citizen of the Republic of France, and a resident of Lyons-Vaise, France, have 5 invented certain new and useful Improvements in and Relating to Water-Tube Boilers, of which the following is a specification.

This invention relates to improvements in and relating to water-tube boilers.

- 10 In all kinds of water-tube boilers it is necessary for economy of fuel and to increase the durability of the tubes that the water, which is a better conductor of heat than steam, should remain in contact with the walls of 15 the tubes it passes through. For this purpose it is important to prevent the formation of globules of steam occupying the whole cross-section of the interior of the tubes, which formation would expose the tubes to burning. 20 For this purpose a thin plate of steel or other suitable metal is arranged in the interior of each water-tube, said plate passing from the lower end of the tube up to and slightly beyond the water-level in order that the plane 25 of the plate may be generally transverse to the direction of firing.

- In order that my invention may be easily understood, I have annexed to the specification as an example drawings showing the improvement which forms the object of the present application applied to a boiler of the system patented to me, No. 676,485, application 30 dated August 21, 1900. However, the invention can also be applied to any kind of 35 water-tube boiler—that is to say, to any system of steam-generators in which the water penetrates in the tubes in order to be heated.

- In the annexed drawings, Figure 1 is a vertical section of the boiler. Fig. 2 is a horizontal 40 section thereof on line A B of Fig. 1. Fig. 3 is a section and elevation showing a tube with a plate therein, the plate being notched or cut away on its edges, this figure being on a larger scale than the previous figures. 45 *a a* are the water-tubes of the boiler, and *b b* the plates arranged in the interior of each

tube. It is evident that the tubes thus shown have each their lower horizontal part and their vertical part, which is directed toward the center of the boiler, much more productive of steam than those parts which are diametrically opposed to them and that if the plate dividing the tube into two almost equal parts has a space left between its edges and the interior wall of the tube the part of the 50 tube remote from the flame will form a reserve of water in order to fill the empty spaces in proportion as bubbles are formed along the plate. It will be understood that the plate must necessarily have its plane perpendicular or transversely arranged to the flame and that a space should be left between its edges and the inner wall of the tube. It should be further stated that the said plates may be perforated by small holes, and even 55 replaced by wire-gauze of small mesh. The effect produced—viz., the prevention of the formation of the steam-globules—is always the same.

It should be mentioned that the arrangement of the plates in the interior of the tubes gives a great uniformity to the water-level in all parts of the generator, however great the quantity of steam required.

Having now particularly described and ascertained the nature of my said invention and in what manner the same is to be performed, I declare that what I claim is—

A boiler with tubes for vaporizing water, said tubes being open at both extremities and 60 having on the interior of each a plate arranged normally with the direction of the fire and characterized by this, that each plate is notched upon its edges.

In testimony whereof I have signed my 65 name to this specification in the presence of two subscribing witnesses.

CHARLES PHILIPPE ALTMANN.
